3 Sheets-Sheet 3

Inventor:
Frederick Francis Fecher
By his Attorney
Edmond Congar Brown

UNITED STATES PATENT OFFICE.

FREDERICK FRANCIS FECHER, OF ROCKVILLE CENTER, NEW YORK, ASSIGNOR TO THE BECK DUPLICATOR COMPANY, A CORPORATION OF NEW YORK.

DUPLICATOR.

Application filed August 8, 1925. Serial No. 48,990.

To all whom it may concern:

Be it known that I, FREDERICK FRANCIS FECHER, a citizen of the United States, and a resident of Rockville Center, in the 5 county of Nassau and State of New York, have invented certain new and useful Improvements in Duplicators, of which the following is a specification.

The invention relates to duplicators, more 10 particularly to that form of duplicator in which a negative or reversed impression of matter to be copied is impressed upon an adhesive duplicating surface, and positive impressions taken therefrom by bringing 15 sheets of paper or the like in contact therewith; and has for one of its principal objects to provide simple, efficient and economical means whereby the rapid handling of sheets of paper and the feeding of the same 20 to the adhesive duplicating surface of the duplicator and the stripping of the same therefrom, is facilitated.

The invention consists in the novel construction, arrangement and combination of 25 various devices, elements and parts, as set forth in the claims hereof, one embodiment of the same being illustrated in the accompanying drawings and described in this specification.

30 In the said drawings,

Fig. 1 is a perspective view of one embodiment of my invention;

Fig. 2 is a plan view thereof, the swinging paper-holding device being removed; 35 and

Figs. 3 and 4 are fragmentary side views showing the paper-stripping mechanism in different positions.

In carrying my invention into effect in 40 the embodiment thereof which I have selected for illustration in the accompanying drawings and description in this specification, I provide a main frame structure of any form suitable for the purpose, such as 45 may comprise a base having mounted thereon frame members 12, suitably connected together so as to make a frame of sufficiently rigid construction. A bed 16, secured between said frame members, comprises or serves as a support for an adhesive

duplicating surface 14. This adhesive duplicating surface may be either the surface of the bed itself, or a portion of a film or strip secured to the bed, or there may if desired be a comparatively long sheet the portions of which not in use may be stored upon rollers journaled between said frame members, according to a construction which is well understood in the art to which said duplicators relate. As the means for the 55 storage of the film and for winding and unwinding same therefrom and passing same over the support, as the bed 16, form no part of the present invention, it is not necessary to describe the same in detail.

Adapted to co-operate with the devices above referred to, I provide an attachment comprising a paper-support or table member, which is preferably in the form of a shallow tray, having a bottom 23 covering 70 the entire area with the exception of an opening 20 at one end, as will be seen in Fig. 1. The tray may be provided with side and end walls 21 and with a paper-depressing member 30 which lies over the opening 75 20 in the floor of the tray, the function of which is to operate, when depressed, to bring the lowermost sheet of paper into contact with the adhesive duplicating surface. This paper-depressing member is mounted upon 80 a shaft 31, and springs 32 may be provided, tending to keep the member 30 normally out of contact with the paper.

The tray is provided with a handle 33 for convenience in operating the same, and with 85 a hook 35 adapted to engage with a stud 36 in one of the side frames, for the purpose of holding the tray in its lowered position when not in use. The tray is pivotally supported on the frame by means of lugs 37 which engage with a rod 38, the spiral spring 39 tending to hold the paper-tray in the elevated position shown in Fig. 1.

At the right-hand side of the machine is a rod 40, the ends of which are secured in 90 brackets 41 in one of the side frames of the machine.

Mounted on the rod 40 is a sliding member 44 having a laterally extending frame 45 in which is journaled a roller 46. This 100

frame is also provided with a handle 47 for convenience in operating the same. Also mounted on the rod 40 is a second sliding member 50 having a laterally extending frame 51 in which is journaled a roller 52. Secured to the sliding member 44 is a pivoted latch 55 which is adapted to engage with a stud 56 on the second sliding member 50 and thereby couple the two sliding members together when desired. A spring 57 tends to depress the latch 55 into engagement with such stud 56. On the side frame 12 is a stop 60, adapted when the sliding members are moved up to the same, to elevate the latch 55 and disengage it from the stud 56. Near the other end of the side frame is a casing 61 in which is a coiled spring to which is secured a cord 62 secured to the sliding member 50, and tending to draw the same back along the rod 40 when disengaged from the sliding member 44. An adjustable stop 63 may be set at any desired point upon the rod 40 to prevent the sliding members from passing too far back.

65 represents a sheet of paper, most of which is lying flat upon the adhesive duplicating surface but one end of which, indicated at 66, is shown raised up above the adhesive duplicating surface and passing between the rollers 46 and 52.

The operation of the above described embodiment of my invention is as follows: Upon the paper-supporting device is placed, face downward, a sheet of paper bearing the matter which it is desired to copy, the same being written or printed with so-called hectographing ink, and upon this original may be placed any number of sheets of blank paper upon which it is desired to copy the matter transferred from the original to the adhesive duplicating surface. If it is desired to position said sheets of paper at any particular place upon the paper-supporting device, adjustable side and end stops 45 may be employed, which, however, form no part of the present invention. It will be understood that the ends of the sheet of paper must always lie over the opening in the floor of the paper-supporting member, and that after the paper is placed in position the paper-depressing member 30 is swung down into position over the ends of the sheets of paper. The original and blank sheets of paper being thus in place upon the paper-supporting member, the pile of paper may if desired be steadied by placing the hand upon the same, although ordinarily this will not be necessary, and the same depressed so that it comes down upon the machine. The paper-depressing member 30 is then operated, which forces a portion of the paper, or if there are a number of sheets of paper on the tray, a portion of the lowermost sheet, down upon the adhesive duplicating surface, to which it adheres. In the

embodiment of the invention which is now being described, the lowermost sheet of paper will be the original containing the matter desired to be transferred to the adhesive duplicating surface. The tray is then elevated, and as the paper is held by the adhesive duplicating surface it is drawn out from under the other sheets of paper and lies flat upon the adhesive duplicating surface, except that the back end of the sheet, shown at 66 in Fig. 1, is prevented from falling upon the adhesive duplicating surface by means of the roller 52. The sliding frame 44 at the time of lowering the paper-tray and depositing the sheet of paper, is toward the front of the machine, and the sliding frame 50 at the back of the machine, both as shown in Fig. 4, but as soon as the paper has been laid upon the adhesive duplicating surface, the frame carrying the roller 46 is moved backward into the position shown in Fig. 1, the roller serving to depress the paper firmly upon the adhesive duplicating surface. When the same reaches the position shown in Fig. 1, the latch 55 engages with the pin 56 on the frame 50, thus locking the two members together and holding the upturned edge 66 of the paper between the rollers 46 and 52. The sliding members are then drawn forward by means of the handle 47, the operator meanwhile holding the edge of the paper 66 and drawing it gently upwards as the forward movement of the rollers between which the paper lies strips the same from the adhesive duplicating surface. Upon the sliding frames reaching the forward end of the machine, the paper is entirely disengaged from the adhesive duplicating surface and is removed by the operator, and the latch 55, coming in contact with the stop 60, is disengaged from the sliding frame 50, whereupon the latter is drawn backward by the spring 61 which winds up the cord 62. The roller 52 being then in its backward position, and the roller 46 in its forward position, the adhesive duplicating surface is ready to receive another sheet of paper, which is deposited thereon as before, the frame 44 pushed backward, and the whole operation above described repeated as many times as may be desired.

When the machine is not in use, the paper-tray may if desired be held downward in a safe position by means of the hook 35 and stud 36.

I do not limit myself to the particular form of construction and combination of parts which I have above described and shown in the accompanying drawings, as it is obvious that many changes in detail can be made without departing from the spirit and scope of the invention.

I do not limit myself to a form of construction in which the paper-supporting

member is pivotally mounted so as to swing in a vertical plane over the other parts of the mechanism. I consider such a construction preferable, but it is obvious that the paper-supporting member might be otherwise swingingly mounted, or slidably mounted, the function and operation of the same remaining substantially as above described.

The advantages of my invention will be obvious from what has been above said with regard to its construction and method of operation.

Having thus described my invention, what I claim as new and desire to secure by Letters Patent is as follows:

1. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, but to be approximated and coupled together when the paper-supporting member is raised, whereby a portion of the sheet of paper is held between the rollers of said frames, which are then adapted to strip said paper from said adhesive duplicating surface.
2. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on

said duplicator, a roller rotatably mounted in said frame, adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, but to be approximated and coupled together when the paper-supporting member is raised whereby a portion of the sheet of paper is held between the rollers of said frames, which are then adapted to strip said paper from said adhesive duplicating surface; means adapted to couple said frames together and means adapted to automatically release said coupling means, whereby said rollers may be separated from each other.

3. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, but to be approximated and coupled together when the paper-supporting member is raised, whereby a portion of the sheet of paper is held between the rollers of said frames, which are then adapted to strip said paper from said adhesive duplicating surface, said frames being adapted to be widely separated from each other when said paper-supporting member is swung down toward said adhesive duplicating surface, but to be approximated and coupled together when the paper-supporting member is raised, whereby a portion of the sheet of paper is held between the rollers of said frames, which are then adapted to strip said paper from said adhesive duplicating surface; means adapted to couple said frames together, means adapted to release said coupling means, and means adapted to automatically separate said frames from each other.

4. In a duplicator, the combination with a supporting frame or base, a bed, and an adhesive duplicating surface upon said bed adapted to receive a sheet of paper and to cause same to adhere thereto when a portion

of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, but to be approximated and coupled together when the paper-supporting member is raised, whereby a portion of the sheet of paper is held between the rollers of said frames, which are then adapted to strip said paper from said adhesive duplicating surface; means adapted to couple said frames together, means adapted to release said coupling means, and means adapted to draw said second-named frame away from said first-named frame.

5. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, but to be approximated and coupled together when the paper-supporting member is raised, whereby a portion of the sheet of paper is held between the rollers of said frames, which are then adapted to strip said paper from said adhesive

duplicating surface; means adapted to couple said frames together, means adapted to release said coupling means, means adapted to draw said second-named frame away from said first-named frame, and means adapted to limit the travel of said second-named frame. 70

6. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a paper-supporting member adapted to support a plurality of sheets of paper or the like movably mounted over said adhesive duplicating surface and provided with an opening in the bottom adapted to permit a portion of a sheet of paper held upon said paper-supporting member to be depressed so as to come in contact with said adhesive duplicating surface, a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, said frames being adapted to be widely separated from each other when said paper-supporting member is swung down toward said adhesive duplicating surface, so that said first-named frame shall be in front of the forward end of the paper-supporting member when same is fully depressed, but to be approximated and coupled together when the paper-supporting member is raised whereby a portion of the sheet of paper is held between the rollers of said frames, which are then adapted to strip said paper from said adhesive duplicating surface; means adapted to couple said frames together, means adapted to release said coupling means, and means adapted to draw said second-named frame away from said first-named frame.

7. In a duplicator, the combination with 115
a supporting frame or base, a bed, and an
adhesive duplicating surface upon said bed
adapted to receive a sheet of paper and to
cause same to adhere thereto when a portion
of said sheet of paper is brought into contact 120
with the same; of a paper-supporting member
adapted to support a plurality of sheets of paper or the like movably
mounted over said adhesive duplicating
surface and provided with an opening in the 125
bottom adapted to permit a portion of a
sheet of paper held upon said paper-supporting
member to be depressed so as to come in
contact with said adhesive duplicating
surface, a frame slidably mounted on 130

- 7 said duplicator, a roller rotatably mounted in said frame adapted to depress a sheet of paper upon said adhesive duplicating surface, a second frame slidably mounted on 5 said duplicator, a roller rotatably mounted in said second frame adapted to hold a portion of said sheet of paper away from said adhesive duplicating surface, said frames being adapted to be widely separated 10 from each other when said paper-supporting member is swung down toward said adhesive duplicating surface, so that said first-named frame shall be in front of the forward end of the paper-supporting member 15 when same is fully depressed, but to be approximated and coupled together when the paper-supporting member is raised, whereby a portion of the sheet of paper is held between the rollers of said frames, 20 which are then adapted to strip said paper from said adhesive duplicating surface; means adapted to couple said frames together, means adapted to release said coupling means, means adapted to draw said 25 second-named frame away from said first-named frame, and means adapted to limit the travel of said second-named frame.
8. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a frame slidably mounted on said duplicator, a roller rotatably mounted in said frame adapted to depress a sheet of paper upon said adhesive duplicating surface, a second frame slidably mounted on said duplicator, and a roller rotatably mounted in said second frame adapted to hold a portion of said sheet of paper away from said adhesive duplicating surface, means adapted to couple said frames together, means adapted to release said coupling means, and means adapted to draw said second-named frame away from said first-named frame when the same are uncoupled.
9. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a frame slidably mounted on said duplicator, a roller rotatably mounted in said frame adapted to depress a sheet of paper upon said adhesive duplicating surface, a second frame slidably mounted on said duplicator, and a roller rotatably mounted in said second frame adapted to hold a portion of said sheet of paper away from said adhesive duplicating surface, means adapted to couple said frames together, means adapted to release said
- coupling means, means adapted to draw said second-named frame away from said first-named frame when the said frames are uncoupled, and means adapted to limit the movement of said second-named frame.
10. In a duplicator, the combination with a supporting frame or base, and a paper-adherent member thereon adapted to receive a sheet of paper fed thereon and to cause same to adhere thereto when a portion of said sheet is brought into contact therewith; of a paper-supporting member adapted to support a plurality of sheets of paper or the like, said paper-supporting member being movably mounted over said paper-adherent member and being provided with an opening in the bottom adapted to permit a portion of a sheet of paper held upon said paper-supporting member to be depressed so as to come in contact with said paper-adherent member, means located over said opening adapted to depress a portion of a sheet of paper on to said paper-adherent member, means slidably mounted upon said supporting frame comprising a roller adapted to depress a sheet of paper upon said paper-adherent member, means slidably mounted on said supporting frame comprising a roller adapted to hold a portion of said sheet of paper away from said paper-adherent member, and devices adapted to couple said sliding means together and to release one from the other: the said rollers being contiguous when said sliding means are coupled together and being adapted to receive between them a portion of said sheet of paper, whereby when said coupled rollers are moved over said paper-adherent member, they co-operate in stripping said sheet of paper from said paper-adherent member.
11. In a duplicator, the combination with a supporting frame or base, a bed, and an adhesive duplicating surface upon said bed adapted to receive a sheet of paper and to cause same to adhere thereto when a portion of said sheet of paper is brought into contact with the same; of a frame slidably mounted on said duplicator, a roller rotatably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating surface, and means adapted to couple said frames together.
12. In a duplicator, the combination with a supporting frame or base, a bed, and an adhesive duplicating surface upon said bed adapted to receive a sheet of paper and to cause same to adhere thereto when a portion of said sheet of paper is brought into contact with the same: of a frame slidably mounted on said duplicator, a roller rotat-

ably mounted in said frame adapted to depress a sheet of paper upon said adhesive duplicating surface, a second frame slidably mounted on said duplicator, a roller rotatably mounted in said second frame adapted to hold a portion of said sheet of paper away from said adhesive duplicating sur-

face, means adapted to couple said frames together, and means adapted to release said coupling means.

In witness whereof I have hereunto signed my name this 28th day of July 1925.

FREDERICK FRANCIS FECHER.
